CLAIM

The ornamental design for a cross-beam for a weight rack, as shown and described.

DESCRIPTION

FIG. 1 is a top, front, left perspective view of a cross-beam for a weight rack, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front, left perspective view thereof, shown with exemplary environment.

The broken lines depict portions of the cross-beam for a weight rack that form no part of the claimed design. The zig-zag and broken-away portions show the boundary of the claim and indicate that the appearance of any portion of the article between the zig-zag broken lines forms no part of the claimed design. The additional broken lines in FIG. 8 show environment and form no part of the claimed design.
